COMBINED CLOSURE AND DISPENSER

Louis Koukal, 402 E. 78th St., New York, N.Y.

Filed Nov. 26, 1963, Ser. No. 77,577

Term of patent 14 years

(Cl. D58—26)

FIG. 1 is a top perspective view taken from the front and one side of a combined closure and dispenser showing my new design;

FIG. 2 is a bottom plan view thereof;

FIG. 3 is a cross sectional view thereof taken on line 3—3 of FIG. 1;

FIG. 4 is an exploded view thereof with the tube shown broken away for convenience of illustration; and

FIG. 5 is a bottom perspective view taken from the front and side opposite that of FIG. 1 with the dispenser in open position.

I claim:

The ornamental and new design for a combined closure and dispenser, substantially as shown and described.
